UNITED STATES PATENT OFFICE.

CAMILLE E. ROY, OF CHICAGO, ILLINOIS.

TRAY.

1,353,273.

Specification of Letters Patent. Patented Sept. 21, 1920.

Application filed April 3, 1920. Serial No. 371,019.

To all whom it may concern:

Be it known that I, CAMILLE E. ROY, a citizen of the United States, and a resident of the city of Chicago, in the county 5 of Cook, State of Illinois, have invented certain new and useful Improvements in Trays; and I do hereby declare that the following is a full, clear, and exact description of the same, reference being had to the accompanying drawings, and to reference-numbers marked thereon, which form a part of this specification.

This invention relates more particularly to trays used by jewelers and jewelry salesmen for the display and transporting of 15 jewelry.

This invention also relates to such trays as are used for window and show-case display.

20 Trays of this sort have heretofore been made of wood with a fabric bottom.

It is an object of this invention to produce a tray so made that all parts may be stamped from sheet metal of a light nature 25 preferably such as aluminum.

It is an object of this invention to construct a tray in which the adjustability of the partitions will permit a variation in the size of the pockets.

30 It is also an object of the invention to produce a tray so made as to insure retention of the partitions when the tray is being handled.

It is further an object of this invention 35 to produce a tray having a minimum number of interchangeable standardized elements.

It is also an object of this invention to produce a tray in which a piece of paper 40 may be placed between the bottom of the tray and the partitions and being held in place by the said partitions.

These objects and other minor objects are 45 respectively attained by making the frame continuous and inverted U-shaped in cross-section, and by making the bottom rim likewise continuous and of such cross-sectional shape as to enable it to close the frame from below; by providing the frame and the division walls of the tray with spaced openings 50 with which the ends of said walls may be removably engaged; by making the opposite walls of the tray resilient so that said walls may return to and remain in their normal 55 positions after being sprung apart to admit

the flanges on the end of the partitions; and by providing openings in the walls of the frame as well as in the partitions, for the retention of said partitions.

In the appending drawings Figure 1 is 60 a plan view of the tray in assembly.

Fig. 2 is an end elevation of the tray.

Fig. 3 is a side elevation.

Fig. 4 is a transverse cross-section taken along the line 4—4 of Fig. 1. 65

Fig. 5 is a perspective view of the tray showing a paper insert.

Fig. 6 is an enlarged detail view of the main partitions.

Fig. 7 is an enlarged detail view of smaller 70 or intermediate partitions.

Fig. 8 is a section taken along the line 8—8 of Fig. 1 and shows the method of connecting the partitions.

Fig. 9 is fragmentary view of a partition 75 in a modified form.

As shown in the drawings, 1 is the body or frame of the tray which is punched and drawn into an inverted U-shape in cross-section and is more clearly shown in Fig. 4 80 and is so formed as to comprise a shorter outer wall 3, an inner wall 4 with a flange 2 projecting at right-angles toward the inner part of the tray thereby forming a body member which is integral and made of the 85 same piece of metal with rounded corners 5 giving the tray an exceptional degree of rigidity.

Along the inner wall 4 of the frame 1 I have provided a plurality of perforations 6 90 uniformly spaced apart to receive the flanges 12 and 14 of partitions 7 and 8 respectively.

The main partitions 7 and the intermediate partitions 8 are more clearly shown in Figs. 6 and 7. The numeral 9 refers to the 95 space or pocket in which the display card carrying the jewelry is placed and the numeral 10 refers to the fabric bottom which is stretched across the frame and is fastened to the rim 11 by means of glue or any other 100 suitable means.

In Fig. 6, the numeral 7 refers to the main partition which is inverted U-shaped in cross-section terminating into the flanges 13 and having lugs 12 projecting out from its 105 ends, which lugs fit into the perforations 6 of the body member 1.

Numerical 18 refers to the perforations or openings in the main partition 7, for the reception and retention of the lugs 14 pro- 110

jecting out from the ends of the intermediate partition 8.

The intermediate partition 8, Fig. 7, is of the same construction as that of the main partition 7, terminating into the flanges 15 and having lugs 14 projecting out from its ends which fit into the perforations 18.

Fig. 8 is a section taken along line 8—8 of Fig. 1 and more clearly explains the position 10 of the interlocking members of the partitions 7 and 8 in assembly.

Fig. 9 is a modified form of the partition 7 with the lugs 12 removed so that the partition can be slidably situated between the 15 opposite sides of the frame.

Fig. 5 is a perspective view of the tray showing a piece of paper 19, inserted on the bottom of the tray and terminating into the ends or wings 20 and 21 which can be laid 20 or folded over the top of tray when it is filled, thereby forming a top or cover for the tray and its contents.

Referring again to Fig. 4, 11, is the bottom rim of the frame 1 and is made of one 25 piece with a curved surface 15, to which the fabric is fastened, giving the tray a round surface about the entire lower edge.

The curved surface 15 is carried to a sharp recess 17, just inside of the short outer 30 wall 3 and terminates into a flange 16 which is carried around the lower edge of the wall 3.

By this construction, the sharp recess 17 permits me to make the outer edge of the 35 fabric invisible and prevents the said fabric from being easily removed.

The numeral 22 refers to the inner edge of the rim 11 which is carried around the

inner edge of flange 2 thereby strengthening said flanges and removing the sharp edges. 40

I claim:

1. A tray including a continuous stamped frame presenting an inverted U-shape in cross-section, and having a stamped bottom extending just beyond the inner edge of 45 said frame.

2. A tray including a stamped frame presenting an inverted U-shape in cross-section, and having a flange and a stamped bottom both extending just beyond the inner edge 50 of said frame.

3. A tray including a stamped frame presenting an inverted U-shape in cross-section, the outer wall of said frame being of less vertical extent than the inner wall thereof 55 and a bottom for said frame terminating at said outer wall.

4. A tray including a stamped frame presenting an inverted U-shape in cross-section, the outer wall of said frame being of less 60 vertical extent than the inner wall thereof, and a bottom for said frame terminating at said outer wall and having a groove for the reception of the said outer wall.

5. A tray including a stamped frame presenting a U-shape in cross-section, the outer wall of said frame being of less vertical extent than the inner wall thereof, and a bottom for said frame terminating at said outer wall and having a groove for the reception 65 of said outer wall and another additional and exterior groove for receiving the fabric constituting the bottom of the tray. 70

In witness whereof I have affixed my signature this 29 day of March, A. D. 1920.

CAMILLE E. ROY.
